UNITED STATES PATENT OFFICE.

ROBERT CRAIG AND GEORGE E. WOOD, OF DAYTON, OHIO, ASSIGNEES, BY MESNE ASSIGNMENTS, TO DAYTON SCALE COMPANY, OF DAYTON, OHIO, A CORPORATION OF NEW JERSEY.

MOTOR-DRIVING DEVICE FOR SLICING MACHINES.

Application filed August 16, 1922. Serial No. 582,106.

This invention relates to improvements in motor driving devices for slicing machines and more particularly is directed to an improved motor drive device for a bread cutter or slicer of the type shown and described in the patent to A. R. Mulder, No. 1,289,516.

Bread cutters of this general type usually include a handwheel or fly-wheel usually directly mounted upon the drive shaft or 10 knife shaft of the machine. The handwheel is provided with a grip or handle which is turned by the operator.

The present improvement is directed to a simple motor mounting and driving device 15 which may be readily attached to machines of this type to permit the same to be driven by power.

Broadly, the invention is directed to an improved motor mounting in which the motor assembly may be bodily swung up or down to bring a friction driving pulley into or out of engagement with the periphery of the hand- or fly-wheel. A controlling switch is also provided which switch is interconnected to the motor displacing means whereby current will be supplied to the motor when the driving pulley is engaged and whereby the motor circuit will be automatically interrupted upon the disengagement of the pulley. Resilient means such as a spring are provided for holding the driving pulley in engagement with the fly-wheel and this spring also serves to close the switch.

35 In the drawings:

Fig. 1 is a side view of one end of the machine.

Fig. 2 is an end detail view with the driving pulley in engagement.

40 Fig. 3 is a similar view with the pulley disengaged.

In more detail, 10 is the part of the machine frame which rotatably carries the drive shaft 11 having a fly-wheel or hand-wheel 12 mounted upon one end thereof. 45 13 is the usual hand-grip on the hand-wheel. Extending upwardly from and fixed to the machine frame are a pair of brackets 14 which carry pivot studs 15, which extend 50 into depending lugs on the motor supporting frame or sub-base 16. Fixedly mounted upon the sub-base is a motor 17 having a friction driving pulley 18 extending over the periphery of the fly-wheel. Also fixed

to the sub-base is a switch housing containing a rocking type knife switch and having a link 19 connected to the switch blade 20, and having its lower end fixed to one of the brackets 14.

To normally maintain the pulley with a 60 yielding pressure against the fly-wheel, a spring 21 is provided which spring is connected to the sub-base 16 and to the main frame 10.

To shift the motor driving pulley out of 65 contact with the fly-wheel and to concurrently open the switch 20, there is provided a bell crank shaped handle 22. This is pivoted upon one of the brackets 14. A toggle link 23 is connected to the bell crank and 70 at its upper end is provided with a shouleder portion 24 adapted to engage the lower surface of the sub-base. The upper end of the link 23 has an extended guiding finger portion 25 which extends through a slot or 75 hole in the sub-base.

To disengage the driving pulley and open the switch the operator depresses the handle 22 and swings it from the position shown in Fig. 2 to the position shown in Fig. 3. 80 Toggle link 23 is elevated and abutting against the sub-base swings it about its pivots, stretching spring 21 and opening the knife switch 20. The machine may be operated by hand in the usual manner. If 85 it is now desired to drive the machine by the motor, the operator lifts the handle 22 sufficiently to break the toggle formed by link 23. Thereafter the spring 21 draws downwardly upon the sub-base and engages 90 the driving pulley yieldingly with the fly-wheel. The downwardly swinging movement of the motor sub-base also causes the switch 20 to be closed and supply current to the motor, from the supply line 26. 95

Preferably the driving pulley is provided with a protecting housing or cover 27 which is fastened to the end of the motor frame as shown in Fig. 1.

The motor driving attachment may be 100 readily applied to machines already in use, as will be readily understood. All parts including the controlling switch form a compact unit and may be readily manufactured and assembled. The slicing machine may 105 readily be operated either by hand or power and by compelling the disengaging of the driving pulley at each time the motor drive

is suspended, the contour of the driving pulley is preserved and flattening which would otherwise develop if the machine should stand idle for extended time periods, is obviated.

What we claim is:—

1. In a device of the class described, in combination with a pivotally supported motor base, of a motor carried thereby and having a driving pulley, resilient means for swinging the motor base and maintaining the driving pulley in engagement with a wheel to be driven, and means including a toggle linkage and a manually operable handle for oppositely swinging the motor frame to disengage the pulley and to maintain such disengagement upon the release of the handle.

2. In a device of the class described, in combination with a pair of supporting brackets, of a motor sub-base pivoted thereto, a motor carried upon said sub-base and having a driving pulley, a spring connected with said sub-base and normally tending to draw said driving pulley into engagement with a wheel to be driven thereby, a bell crank hand lever pivoted to one of said brackets, a toggle link connected therewith and extending into cooperative relation with the sub-base, said bell crank and toggle link

upon being swung in one direction being adapted to disengage the driving pulley and to thereafter maintain such disengagement, and when swung in the opposite direction permitting the driving pulley to engage the driven wheel under the power of the spring, and a switch automatically operated to close the motor circuit upon the engagement of the pulley and operated to open the circuit upon the disengagement of the pulley.

3. In combination with fixed bracket members adapted for attachment to the frame of a bread-slicing machine adjacent the driving hand wheel thereof, a motor sub-base pivotally mounted upon said brackets, a motor carried thereby, a driving pulley thereon, a hand lever having a locking toggle link for disengaging the driving pulley and hand wheel by swinging the motor sub-base, a spring for engaging the driving and driven pulley and yieldingly maintaining the same in contact, said hand lever being manually adjustable to break the toggle lock and permit the spring to draw the pulley and wheel together.

In testimony whereof we hereto affix our signatures.

ROBERT CRAIG.
GEORGE R. WOOD.
